United States Patent Office.

JAMES E. JOUETT, OF NEW YORK, N. Y.

Letters Patent No. 67,556, dated August 6, 1867.

IMPROVED CHAIR AND COUCH.

The Schedule referred to in these Letters Patent and making part of the same.

TO ALL WHOM IT MAY CONCERN:

Be it known that I, JAMES E. JOUETT, of New York, of New York county, in the State of New York, have invented certain new and useful Improvements in Combined Chair and Couch Apparatus; and I do hereby declare that the following is a full and exact description thereof, reference being had to the accompanying drawings making part of this application.

My invention relates to certain new and useful improvements on the combined "chair, couch, and stretcher," patented to me on the sixth day of November, 1866.

My present invention has for its objects to render such an apparatus still more desirable and convenient, both for field service and as an article of household furniture, by embodying in it a more complete and ready means of putting it together and taking it apart, and a better system and arrangement of the several parts; and to these ends my present invention consists in the several characteristic features of construction herein-after more particularly described and claimed.

To enable those skilled in the art to make and use my invention, I will proceed to describe more fully the construction and operation of an apparatus embracing my several improvements, referring by letters to the accompanying drawings, in which—

Figure 1 is a sectional elevation of my improved "combined chair and couch."

Figure 2 is a similar view of the same in a different adjustment, showing a chair of different proportion from that seen at fig. 1; and

Figure 3 is an elevation showing the apparatus adjusted to constitute a couch.

Figures 4, 5, 6, and 7 are detail views, which will be presently referred to.

In the several figures the same parts are designated by the same letter of reference.

A and B are the main bars, and b^1 b^2 and c c^2 the cross-bars, which, when put together, constitute the two rectangular frames, which are pivoted together at z by means of metallic pivots or screw-bolts, provided with suitable nuts. The longitudinal bars A B are cut away, where they come together at e , in the manner and for the purposes substantially as described in my Letters Patent referred to. D is the flexible apron, made of any suitable material, such as canvas, for instance, and formed or made up with hems or pockets for the reception of the cross-bars g i . This apron D has at or near one end two such pockets, (as illustrated at 5 6, see fig. 6,) the object of which is that the cross-bar adapted to fit in said pockets may be placed in one or the other, as occasion requires, to admit of a greater or less degree of distension of the apron, as will be presently more fully explained. One of the cross-bars or apron-sticks g is made of the shape seen at fig. 4, being larger in the middle portion than at either end; the other one, i , is made of the peculiar form seen at fig. 5, and the two cross-bars c and b^1 are flattened on one side, as seen in the sections, in lieu of being perfectly circular in cross-section, as shown in my said Letters Patent. The object and advantage in making these cross-bars, as shown, are to have a flat or plane surface presented for the limbs of a person sitting on the chair, (when formed either by the adjustment seen at fig. 1, or by that seen at fig. 2.) In the latter adjustment, the object and advantage of the peculiar form of bar i are clearly seen. It will be seen that by virtue of the depression along the bar i , it assumes a position such that its upper surface lies about level with the flattened surface of bar b^1 , so as to present a comfortable rest for the legs and seat of the person occupying the chair. The bars b^1 b^2 c c^2 are all made with screws, and provided with nuts z , as seen at fig. 7, so that they can be coupled to and disconnected from the bars A B with great facility, and at the same time, when coupled or screwed in, will remain rigidly in adjustment. The said bars may be formed with right and left-hand screws, as shown at fig. 7, so as to screw into the side pieces A B, the nuts f acting as jam nuts. The peculiar arrangements or different adjustments of the apron and frames together, to form the chairs and couch, are clearly illustrated by the drawings, and need not be further described here. In forming the couch seen at fig. 3, it may be desirous to have the apron pretty taut or tight; to effect this, the cross-bar i is put in the pockets 5 of the apron, to shorten it, as seen, or take up the slack.

The general operation and the uses of the apparatus are about the same as those of the chair and stretcher already patented to me, and need not be further alluded to here.

It will be understood that by the construction of the several parts in the manner described, and their adap-

tation to one another, an apparatus is furnished which is easily and rigidly put together for use, and with equal facility taken apart, and which may be packed up in an exceedingly small space or parcel for transportation, which is a great desideratum in the use of the concern for army purposes.

Having explained the nature of my improvement upon the apparatus patented to me as aforesaid, what I claim as new, and desire to secure by Letters Patent, is—

In combination with the frame and shifting-apron, the flattened cross-bars b^1 and c , the whole arranged and operating in the manner and for the purposes described.

I also claim the cross-bar i of the shape described, so that it will lie even with the cross-bar b^1 , as shown and described, for the purpose described.

I also claim, in combination with the reversible frame and shifting-apron, the apron-sticks with their middle portions enlarged, all as and for the purposes described.

I also claim the employment, in combination with the reversible frame and removable sticks, of a shifting-apron made with a series of pockets, substantially as and for the purpose specified.

In testimony whereof I have hereunto set my hand and seal this day of , 1867.

JAS. E. JOUETT. [L. s.]
